UNITED STATES PATENT OFFICE.

ALONZO H. WESTON AND JOHN ZILLIOX, OF BUFFALO, NEW YORK, ASSIGNEES TO KEY-BOLT APPLIANCE COMPANY, OF BUFFALO, NEW YORK.

PROCESS OF MAKING KEY BOLTS.

1,403,365.

Specification of Letters Patent. Patented Jan. 10, 1922.

Application filed October 22, 1920. Serial No. 418,769.

To all whom it may concern:

Be it known that we, ALONZO H. WESTON and JOHN ZILLIOX, both of the city of Buffalo, in the county of Erie, State of New York, United States of America, have invented certain new and useful Improvements in Processes of Making Key Bolts, of which the following is a specification.

This invention relates to bolts of the type 10 with which a key passing through a slot in the bolt is used instead of a nut. Such bolts have been made by bending upon itself a suitable shaped blank and subsequently forming up the head in suitable dies. See, for example, the bolts described in United States Letters Patent 1,000,445 of August 15th, 1911, and 1,266,334 of May 14th, 1918.

The manufacture of bolts in accordance with the prior art necessitated not only the 20 original rolling of the metal for the blank to a given cross-section, but also a further rolling or shaping of the blank to change its form in longitudinal section or in cross section or in both.

25 This is a fairly satisfactory process if bolts of but one diameter are being made, but when bolts of a number of different diameters are required and of different lengths for each diameter, the provision of rolls for so many 30 different sizes involves too great a capital outlay.

Our object in the present invention, therefore, is to devise a process of making such bolts which will enable us to produce the 35 bolts from metal bars of uniform cross-section, inclusive of bars of standard sizes and shapes such as are obtainable in the open market, without subjecting them to special rolling or shaping processes previous 40 to the bending and heading operations.

We attain our object by bending on itself a straight metal bar of suitable cross-section to bring its parts into proximity but separated, adjacent the bend at least, by a space 45 substantially equal to the desired width of the slot. The blank is then enclosed in a die of the desired size and shape of the finished bolt provided with a form which passes between the parts of the blank to maintain the 50 slot during the succeeding operations.

The ends of the parts of the blank are left projecting, and are then upset to displace the metal thereof longitudinally to substantially fill the die and thus form the unslotted portion of the stem of the bolt.

The upsetting will usually partly, at least, shape the head, but we find that the best results are attained, particularly if a round headed bolt is required, by having the die which displaces the metal longitudinally only 60 partly shape the head, the final shape being given by a separate die in a separate operation.

The details of the process are hereinafter more fully described and the apparatus employed therein illustrated in the accompanying drawings in which—

Fig. 1 is a front elevation of apparatus for bending the blanks;

Fig. 2 a side elevation of the same; 70

Fig. 3 a plan view of the same partly in section;

Fig. 4 a side elevation of the finished bolt;

Fig. 5 a plan view of the same;

Fig. 6 a cross section of the same on the 75 line *a*—*b* in Fig. 5;

Fig. 7 a longitudinal section of the apparatus for upsetting and heading the bolt;

Fig. 8 a transverse section of the holding die; and 80

Fig. 9 a longitudinal section of a bolt illustrating its method of use.

In the drawings like numerals of reference indicate corresponding parts in the different figures. 85

Referring particularly to Figs. 1, 2 and 3, 1 is a mandrel on which the blank 14 in the first place is laid as shown in full lines. 2 are rolls journaled on a head 3, which head in practice will be suitably supported to 90 reciprocate the rolls on each side of the mandrel, these rolls, coming into contact with the blank, bend it over the mandrel as indicated in dotted lines, thus bringing its parts into substantial parallelism. 95

The blank 14 is shown in the drawings as being formed of substantially half round stock of substantially the same cross section at all parts of its length. It must be kept in mind, however, that the process illustrated 100 is applicable to many other forms of blank than that shown, the usual limitation, however, of the form of the blank being that its cross section shall be substantially that of half the slotted portion of the stem of the 105 bolt less half the cross sectional area of the slot.

For certain purposes, which will herein-after appear, it is desirable that the blank along the crown of its rounded side should 110

be flattened or deformed. This is preferably effected by forming a flat 4 in the bottom of the groove of each of the rolls 2. The deformation of the blank is thus effected by pressure between the rolls and the mandrel 1. The bent blank is removed from the mandrel and placed in a holding die 5.

To facilitate the introduction and removal of the blank, the die will usually be 10 divided on the plane $c-d$, that is, in a plane at right angles to the plane of the slot of the finished bolt. In this die, the blank is securely gripped. No means are shown for clamping the parts of the die together, but 15 any ordinary devices would be used for this purpose.

In connection with each die we provide a 20 form to maintain the slot in the slotted portion of the stem of the bolt. Usually this form will be provided by the lugs 6, one formed integrally with each half of the die, which lugs are preferably slightly tapered in cross section to facilitate their disengagement from the slot in the finished bolt.

25 It will be noted that the ends 7 of the two parts of the blank project from the die. Co-operating with the die is an upsetting die 8 having a recess 9 formed therein adapted to engage the opposed ends 7 of the blank 30 to displace the metal therein longitudinally so as to cause the metal to substantially completely fill the die above the lugs 6, thus forming the non-slotted portion of the stem of the bolt as shown particularly in the upper part of Fig. 7 of the drawings. This 35 operation may result in the partial or complete formation of the head of the bolt, depending somewhat on the nature of the head desired. In the drawing the head is shown 40 as having been partly formed by this first upsetting operation.

It will be noted that in Fig. 7 a double die 5 is illustrated and the upsetting die contains also a recess 10 of the desired shape of 45 the finished head. After the first upsetting operation, the position of the upsetting die 8 is changed to bring the recess 10 into alignment with the partially formed head. The second blow of the upsetting die then 50 finishes the head to substantially the shape shown in Figs. 4 and 5 of the drawings. The die is then opened up and the finished bolt removed.

For many purposes, a straight cylindrical 55 bolt is desired and we have illustrated the formation of such a bolt. It will be understood, however, that this method of producing a substantially unslotted portion of the stem of the bolt by flowing the metal of the 60 projecting ends into the die is adapted to the formation of bolts of almost any form of cross section and of various shapes longitudinally other than cylindrical. Further, heads of any desired pattern may be formed 65 on the bolts as may be desired.

We find that this process results in the formation of a bolt possessing many desirable characteristics. Having reference particularly to the formation of a cylindrical bolt from half round material, we find that the outer end of the slot 11, as indicated particularly in Figs. 4 and 9, is somewhat rounded outwardly either way from the middle, which gives the tapered key 12 a good bearing surface when driven from either side. We further find the bending of the half round bar over the mandrel and the substantial gripping of the blank in the holding die during the upsetting operation results in a slight increase in the thickness 75 in the bend of the metal at the end of the bolt which is a desirable characteristic. The bolt will be absolutely true in external contours, which is an important feature in shipbuilding operations, or other constructional 80 work in drawing together plates 13 as indicated in Fig. 9.

Owing to the deformation of the crown of the blank in the bending operation as hereinbefore referred to, a small space is left 90 between the blank and the holding die at each side at points remote from the division of the die. This provides room into which a flow of metal can take place during the upsetting and heading operations. Otherwise 95 some tendency exists for the formation of slight fins or flashes along the sides of the bolt in line with the division between the parts of the die.

While in a bolt formed as shown, there is 100 slightly less cross sectional area of metal in the slotted portion of the stem of the bolt than in the cross section at the bottom of the threads of a bolt threaded with the United States standard thread for the specific bolt diameter, yet owing to the fact that we can employ in the formation of the bolt a steel of such high carbon content that a screw thread cannot be cut therein, a bolt is produced which is of greater strength than 110 threaded bolts as ordinarily employed.

The bending and upsetting operations will usually take place while the metal is at about a cherry red heat.

What we claim as our invention is:—

1. A process of forming a key bolt with a non-slotted stem portion adjacent one end and a slotted portion adjacent the other end which consists in forming a blank by bending on itself a metal bar to bring its parts 120 in proximity to one another; and upsetting the free ends of the parts of the blank sufficiently to form the non-slotted portion of the bolt.

2. A process of forming a key bolt with a non-slotted stem portion adjacent one end and a slotted portion adjacent the other end which consists in forming a blank by bending on itself a metal bar to bring its parts 125 in proximity to one another; and upsetting 130

the free ends of the parts of the blank sufficiently to form the non-slotted portion of the bolt and a head.

3. A process of forming a key bolt with a non-slotted stem portion adjacent one end and a slotted portion adjacent the other end which consists in forming a blank by bending on itself a metal bar to bring its parts in proximity to one another; and upsetting the free ends of the parts of the blank sufficiently to form the non-slotted portion of the bolt and further upsetting the said ends in a separate operation to shape the head of the bolt.
4. A process of forming a keybolt with a non-slotted stem portion adjacent one end and a slotted portion adjacent the other end which censists in forming a blank by bending on itself a metal bar to bring its parts in proximity to one another; holding the blank in a suitable enclosing die and defining and maintaining the slot by means of a transverse form; and upsetting the free ends of the parts of the blank sufficiently to form the non-slotted portion of the bolt.
5. A process of forming a key bolt with a non-slotted stem portion adjacent one end and a slotted portion adjacent the other end which consists in forming a blank by bending on itself a metal bar of substantially the same cross sectional contour at all parts of its length so as to bring its parts in proximity to one another; and upsetting the free

ends of the parts of the blank sufficiently to form the non-slotted portion of the bolt. 35

6. A process of forming a key bolt with a non-slotted stem portion adjacent one end and a slotted portion adjacent the other end which consists in forming a blank by bending on itself a metal bar to bring its parts in proximity to one another; holding the blank in a suitable enclosing die, which is divided longitudinally in a plane parallel to the sides of the slot, and defining and maintaining the slot by means of a transverse 40 form; and upsetting the free ends of the parts of the blank sufficiently to form the non-slotted portion of the bolt, the blank previous to its enclosure in the die being shaped to provide slight clearance between 45 itself and the die longitudinally of the latter and remote from the plane of division.

7. A process of forming a key bolt with a non-slotted stem portion adjacent one end and a slotted portion adjacent the other end 55 which consists in forming a blank by bending on itself a metal bar to bring its parts in proximity to one another and compressing the blank endwise in a die having the form desired for the external contours of the finished bolt and having a transverse form to define and maintain the slot.

Signed at Buffalo, N. Y., this 7th day of October, 1920.

ALONZO H. WESTON.
JOHN ZILLIOX.
